United States Patent

Des. 235,269
Patented June 3, 1975

235,269

TURNSTILE

Theodore Nica, New York, N.Y., assignor to
Perey Manufacturing Co., Inc., New York, N.Y.

Filed July 13, 1973, Ser. No. 379,126

Term of patent 14 years

Int. Cl. D25—02

U.S. Cl. D28—1 B

FIG. 1

FIG. 2

FIG. 3

FIG. 4

FIG. 5

FIG. 6

FIG. 7

FIG. 1 is a perspective view of a turnstile showing my new design.

FIG. 2 is a top plan view of the turnstile shown in FIG. 1.

FIG. 3 is a front elevational view of the turnstile shown in FIGS. 1 and 2.

FIG. 4 is a rear elevational view of the turnstile shown in FIGS. 1-3.

FIGS. 5 and 6 are end elevational views of the turnstile shown in FIGS. 1-4 as viewed from the right and left ends thereof, respectively.

FIG. 7 is a bottom plan view of the turnstile depicted in FIGS. 1-6.

I claim:

The ornamental design for a turnstile, as shown and described.
